UNITED STATES PATENT OFFICE.

HERMAN A. SIEVERT, OF THE UNITED STATES ARMY.

SADDLE.

1,321,397.

Specification of Letters Patent. Patented Nov. 11, 1919.

Application filed November 12, 1917. Serial No. 201,653.

To all whom it may concern:

Be it known that I, HERMAN A. SIEVERT, of the United States Army, residing at Los Angeles, in the county of Los Angeles, State 5 of California, have invented new and useful Improvements in Saddles, of which the following is a specification.

The invention relates to saddles, and relates particularly to the type of saddle 10 shown and described in my Patent No. 1,069,822, dated August 12, 1913; and this invention further relates to certain improvements upon the device shown in said patent, and generally relates to improvements in 15 saddles of that general character.

It is an object of this invention to provide a saddle of simple and effective construction, with certain adjustments, as will be hereinafter explained, for adapting and adjusting 20 the saddle to the back of an animal and for adjusting the saddle to the needs and requirements of different riders. It is an object of this invention to provide a saddle which will automatically adjust itself 25 to the form and contour of the animal's back, under conditions of motion or rest; it is also an object to provide means for adjusting the effective length of the saddle (the distance between the pommel and cantle) to suit different riders; and it is also 30 further an object to provide, in a saddle of the character described, various improvements to make a complete, efficient, simple, easy riding and sightly saddle.

I will explain a preferred form of saddle in the following specification, and, for the purpose of said specification I illustrate the same in the accompanying drawings in which, Figure 1 is a side elevation of my 40 improved saddle; Fig. 2 is a prespective thereof; Fig. 3 is an enlarged section taken as indicated by line 3—3 on Fig. 1; Fig. 4 is an enlarged back view of the saddle; Fig. 5 is an enlarged section taken as indicated 45 by line 5—5 on Fig. 4; and Fig. 6 is an enlarged section taken as indicated by line 6—6 on Fig. 3.

In the drawings I illustrate my saddle as being composed of four main members; 50 these being two side bars 10, a pommel arch 11 and a cantle arch 12. The side bars 10 are constructed so as to afford a seat 13 between the pommel arch 11 and the cantle 14. These side bars 10 are padded as shown 55 at 15, and are preferably hollow and made of pressed or otherwise formed metal 16

covered smoothly, and preferably entirely, with leather or other suitable covering, as shown at 17. The side bars are shaped so as to collectively form the main body of the 60 saddle; and are properly formed to fit upon the back of an animal on opposite sides of the spine, a small space being left at 19 over the animal's spine between the two side bars. The pads extend rearwardly, as shown at 65 15^a, rearward of the cantle 14; and double flaps 21 and 22 are provided. These flaps may be integral continuations of the leather coverings on the upper and under sides of the side bars; and the cinch 23 enters 70 between the flaps, as clearly illustrated in Fig. 2.

The interconnection between the two side bars 10 is preferably entirely pivotal; and effected through the medium of the pommel arch and the cantle arch 12. At the cantle (as elsewhere where the saddle is padded) the interior of the saddle is hollow. The cantle arch 12 is made of a steel or other suitable rod bent preferably to the configuration shown, and having its two ends 12^a 80 bent rearwardly and passing through the rear vertical wall 25 of the cantle; nuts 26 being placed on the ends 12^a to secure them in place. The points where the ends 12^a 85 are thus pivotally connected to the cantle are preferably somewhat laterally removed from the central longitudinal vertical plane of the saddle and from the inner edges of the side bars; so that each side bar, at its 90 cantle, has a relative pivotal movement about a point somewhat removed from its inner edge. This aids materially in allowing the automatic adjustment and adaptation of the side bars to the animal's back. 95 Where this arch passes through the inner wall 27, of each side bar, an opening 28 is provided large enough to allow all the relative movements of adjustment or adaptation. And this opening allows the cantle 100 arch to be readily removed when the nuts 26 are removed. It may be said that it is an object of my invention and a feature of my saddle to be collapsible so as to be easily transported; and for these purposes it 105 is also a feature that my saddle is of extremely light weight.

The pommel arch is also pivotally connected to the opposite side bars at its outer lower ends. This pommel arch is preferably 110 made also of pressed sheet or other metal in the configuration shown at 30, and covered

interiorly and exteriorly by leather or other covering 31. This arch is formed hollow underneath; and its configuration is such as to give great strength with extremely light 5 weight. The arch is ribbed longitudinally, as shown at 45 so as to increase its strength and stiffness and has edge flanges, as indicated at 33 which further stiffen and strengthen it. The arch surmounts the two 10 side bars and is pivotally connected with the two side bars at the pivots 32, at its opposite lower ends; sufficient space being provided within and under the arch to allow the side bars the necessary movement for accommodation 15 to the animal's back. The pivotal points for the pommel arch are, like those for the cantle arch, removed somewhat from the inner edges of the side bars; and may preferably be removed somewhat farther 20 than are the cantle arch pivots; and the pommel pivots may be on lines which, extended, would pass through the cantle arch pivots. I have shown one of the pivotal connections in detail in Fig. 6. The pivot 25 pin 32 passes through the front flange 33 of the arch and also through two ears 34 which project inwardly into the interior of the arch, being connected solidly to the metal body 30 of the arch. I provide a series of 30 lugs 35, projecting from the side bar 10; and the pivot pin 32 also passes through these lugs 35. The forward end of the pivot pin is bent back upon itself as indicated at 32^a and the bent back end is split and slightly 35 spread as shown at 32^b. This bent back end is passed through an opening 30^a in the front flange 33 of the pommel arch; and the expanded end at 32^b prevents the pin from working out, although it may be readily 40 withdrawn by force. This bent back end also gives the pin a double bearing in the thin sheet metal of the arch.

An important feature of my saddle is the longitudinal adjustability of the pommel arch. It will be noted that the lugs 35 and the ears 34 are so spaced that the arch may be moved forwardly from the position shown in Fig. 6. For instance, the ears 34 may be moved into the spaces next forward 45 of those in which they are illustrated in Fig. 6; and then they may be again moved another step forward, when the front ear 34 will be ahead of the front lug 35 and the rear ear 34 will be where the front ear 34 is 50 shown in Fig. 6. By having a larger number of ears and lugs, and by making the spaces between them suitable, the amount of adjustment of the pommel arch may be made as much as desired. Adjusting the pommel 55 arch has the effect of changing the effective length of the saddle; thus suiting the length of the saddle and the position of the pommel to the necessity or the fancy of the rider.

The stirrups 40 are hung from the pommel 60 arch, being hung on straps 41 which are at-

tached to the pommel arch at 42 near its rear edge and near its outer lower ends. Adjustment of the pommel arch longitudinally thus also causes adjustment of the stirrups longitudinally. The stirrups may also be longitudinally adjustable on the pommel arch by providing a plurality of strap openings 42 spaced as shown on the drawings. 70

From the foregoing description, the nature of my invention may be understood. I 75 have proceeded to describe a preferred form of my saddle with some degree of particularity and detail so that my invention may be fully and thoroughly understood; but I do not thereby limit myself to such particulars and details, but reserve to myself the right to make variations and changes as within the scope of the following claims. 80

This application is companion to my co-pending application Serial No. 202,746, filed 85 Nov. 19, 1917, on saddle. In said co-pending application I illustrate and describe, in addition to the constructions herein illustrated and described, certain additional and modified forms of construction and these, so far as relation to this application are concerned, consist principally in modified form of side bar construction and of the cantle pivotal connection. Claims which are generic to both applications are contained in 90 said co-pending application; while this application contains only claims which are peculiar to the construction herein shown. 95

Having described a preferred form of my invention, I claim: 100

1. A device of the character described, comprising in combination a pair of side bars, a pommel arch over said side bars and pivotally connected at each end with the side bars, a cantle arch pivotally connected 105 at each end with the side bars, said pommel arch being longitudinally adjustable in position on the side bars.

2. A device of the character described, comprising in combination a pair of side 110 bars, a pommel arch over said side bars and pivotally connected at each end with the side bars, a cantle arch pivotally connected at each end with the side bars, said pommel arch being longitudinally adjustable in position on the side bars, and stirrups supported 115 from said pommel arch to be longitudinally adjustable therewith.

3. A device of the character described, comprising in combination a pair of side 120 bars, a pommel arch over said side bars and pivotally connected at each end with the side bars, a cantle arch pivotally connected at each end with the side bars, said pommel arch being longitudinally adjustable 125 in position on the side bars, stirrups supported from said pommel arch to be longitudinally adjustable therewith, and said stirrups being longitudinally adjustable on said pommel arch. 130

4. A device of the character described, comprising in combination a pair of side bars, a pommel arch over said side bars and pivotally connected at each end with the 5 side bars, a cantle arch pivotally connected at each end with the side bars, said pommel arch being longitudinally adjustable in position on the side bars, said side bars being formed of pressed sheet metal and being hollow. 10
5. A device of the character described, comprising in combination a pair of side bars, a pommel arch over said side bars and pivotally connected at each end with the 15 side bars, a cantle arch pivotally connected at each end with the side bars, said pommel arch being longitudinally adjustable in position on the side bars, said cantle arch comprising an arched rod having its two ends 20 bent rearwardly and pivotally connected by its rearwardly bent ends to the two side bars.
6. In a device of the character described, a hollow saddle body having hollow side 25 portions formed of metal, the metal being arranged and constructed to form pads adapted to bear upon an animal's back and to form seat pads for the rider.
7. A device of the character described, 30 comprising in combination a pair of side bars, a pommel arch over said side bars and pivotally connected at each end with the side bars, a cantle arch pivotally connected at each end with the side bars, said pommel arch 35 being longitudinally adjustable in position on side bars, said pommel arch being made of pressed sheet metal ribbed lengthwise of the arch.
8. A device of the character described, 40 comprising in combination a pair of side bars, a pommel arch over said bars and pivotally connected at each end with the side bars, a cantle arch pivotally connected at each end with the side bars, said pommel 45 arch being longitudinally adjustable in position on side bars, the pivotal connections between the ends of the pommel arch and the side bars embodying projections on the side bars and arch adapted to be selectively 50 interengaged, and a pivot pin passing through said projections.
9. A device of the character described, comprising in combination a pair of side bars, a pommel arch over said side bars and 55 pivotally connected at each end with the side bars, a cantle arch pivotally connected at each end with the side bars, said pommel arch being longitudinally adjustable in position on side bars, the pivotal connections 60 between the ends of the pommel arch and the side bars embodying projections on the side bars and arch adapted to be adjustably interengaged, and a pivot pin passing
- through said projections, said pivot pin embodying a straight longitudinal portion passing 65 through said projections and through the arch, and having a bent back portion which is split and expanded and passes again through the arch.
10. A device of the character described, 70 embodying in combination a pair of side bars spaced transversely apart and adapted to bear upon an animal's back on opposite sides of the center, said bars having under surfaces conformed and adapted to bear 75 upon the animal and having upper surfaces conformed to provide seating surfaces for the rider, a pommel arch over said side bars and pivotally connected at each end therewith, and a cantle arch over the side bars 80 and pivotally connected at each end therewith, the pivotal connections of the pommel arch being on axes which pass through the cantle pivots.
11. A device of the character described, 85 embodying in combination a pair of side bars, a pommel arch over said side bars and pivotally connected at each end with said side bars, and a cantle arch between side bars and pivotally connected at each end therewith, the cantle pivots being higher 90 than the pommel pivots so that the side bars swing around pivots higher at their cantle end than at their pommel end.
12. A device of the character described, 95 embodying in combination a pair of side bars, a pommel arch over said side bars and pivotally connected at each end therewith, and a cantle arch between the side bars and pivotally connected at each end therewith, 100 the cantle pivots being higher than the pommel pivots so that the side bars swing around pivots higher at their cantle end than at their pommel end, and the pommel pivots being on axes inclining rearwardly 105 upwardly toward the cantle pivots.
13. A device of the character described, embodying in combination a pair of side bars, a pommel arch over said side bars and pivotally connected at each end therewith, 110 a cantle arch between the side bars and pivotally connected at each end therewith, the cantle pivots being higher than the pommel pivots so that the side bars swing around pivots higher at their cantle end than at 115 their pommel end, and said cantle pivots being closer together and closer to a central line between the side bars than are the pommel pivots.
- In witness that I claim the foregoing I 120 have hereunto subscribed my name this 13th day of October 1917.
- H. A. SIEVERT.
- Witness:
V. E. PRICHARD.
